UNITED STATES PATENT OFFICE.

PAUL H. DAVIS, OF CHICAGO, ILLINOIS, ASSIGNOR OF ONE-HALF TO JOHN ELLIOTT JENKINS, OF CHICAGO, ILLINOIS.

TOROIDAL INDUCTION COIL.

Application filed June 22, 1925. Serial No. 38,710.

This invention relates in general to induction coils and more particularly to induction coils of toroidal form and adapted for use in radio apparatus or the like for transferring currents from one circuit to another by inductance, and as an incident thereto, and upon occasion, the current may also be transformed to a higher or lower E. M. F.

A principal object of the invention is to provide such a device that is controllable to vary the coupling between windings and thereby control the inductance. Devices of this character provided heretofore have been of the fixed type and no variation of coupling has been possible.

Another important object is to provide a variable inductance transformer having a confined and closed field. A coil of this type is particularly adapted for use as an oscillator or radio frequency transformer in radio apparatus, as the output may be varied at will and no external field is generated that would disturb other apparatus in the intermediate vicinity.

Another important object is to provide such a device that may be economically manufactured, that is rigid and durable, and that may be mounted as a unit and readily connected into various electrical circuits.

Numerous other objects and advantages of the invention will be apparent as it is better understood from the following description, which, taken in connection with the accompanying drawings, discloses a preferred embodiment thereof.

Referring to the drawings,

Figure 1 is a side elevation of a device embodying my invention;

Fig. 2 is a section taken substantially on line 2-2 in Fig. 1;

Fig. 3 is a section taken substantially on line 3-3 in Fig. 1;

Fig. 4 is a side elevation of the parts shown in Fig. 3 and partly broken away to show details of construction;

Fig. 5 is a section taken substantially on line 5-5 in Fig. 4;

Fig. 6 is a section taken substantially on line 6-6 in Fig. 4 with certain parts omitted;

Fig. 7 is a perspective view showing a detail of construction;

Fig. 8 is a perspective view showing a detail of construction; and

Fig. 9 is a perspective view showing a detail of construction.

To illustrate my invention, I have shown a coil adapted for use as a radio frequency transformer having a fixed winding 11 and rotatable or variable windings 12 and 13, an internal spacing member 14 to which the various windings may be secured, a confining strip 15 for securing the fixed winding 11 to the internal spacing member 14 and brackets 16 to provide a bearing for the rotatable windings 12 and 13.

The fixed winding 11 is preferably of a toroidal form, the separate windings of which may be substantially in the form of a figure 8 to provide two adjacent and parallel fields 17 and 18. Current may be passed through the windings in either direction, and when alternating current is used, such as in radio apparatus, these adjacent fields are rapidly alternating, and to illustrate the invention when a direct current is passing through the wires in one direction, the forces in the field 17 may move in a clockwise direction, at which time the forces in the field 18 would move in a counter-clockwise direction. It will be noted that in any plane cutting the field, such as Fig. 2, there is at all times during the operation of the coil, a left and right hand, or a clockwise or counter-clockwise field.

The internal spacing member 14 is or may be of any suitable insulating material, and is preferably solid, as shown, having a V shaped rim 21 and a pair of shoulders 22 and 23 adjacent the rim and is preferably cut away at 24 to provide a bearing for one or more brackets 16. The brackets 16 may be of any suitable non-magnetic metal and are preferably substantially U shaped having a pair of flanges 25 extending downwardly on each side of the base 26, which may be secured to the internal spacing member 14 by any suitable means and are preferably apertured as at 27 to receive a bolt 28 which may also be provided with a knurled nut 29 and used as a binding post. The upper end of a leg 31 of the brackets 16 is bent at right angles to provide a leg 32 to which the strip

15 may be secured. A leg 33 is preferably formed to provide a pointer 34. The strip 15 may be made of any insulating material and is preferably depressed intermediate its edges to provide a pair of shoulders 35 and 36 for locating the fixed winding 11, and is secured at its opposite ends to legs 32 of the brackets 16 by a screw 37, which may be suitably insulated from the leg 32 of the brackets 16 to provide binding posts for the winding 11.

Rotatable windings 12 and 13 are wound in accordance with the fixed winding, and in the present instance, in cross section are substantially in the form of a figure 8. These coils are preferably mounted by means of angle plates 41, 42, 43 and 44, which may be of any suitable insulating material and are bent along a line 45 to an angle in accordance with the spacing of the coils. In the present instance, I have shown two of the plates bent to an acute angle and two bent to an obtuse angle. The length and width of these angle plates are determined by the size 25 of the winding. Each of these plates is provided with an extension 46 at each end, which is preferably integral with the plate, located at the line of bend and of sufficient length to extend through the brackets to provide a bearing. The plates 41, 42, 43 and 44 are positioned within the coil as shown (Figs. 4, 30 5 and 6) and the extensions 46 at either end thereof are gathered together, and a collar 47 is tightly pressed thereover which provides 35 a cylindrical bearing 48 and secures the windings of the coil in fixed relation. A knurled disk 49 which is apertured at 51 to provide a press fit is pressed over the bearing 48 at one side of the coil. This disk is preferably 40 partly cut away to provide spokes 50 and openings therebetween, and is marked with suitable characters or indicia adjacent the periphery thereof. Lead wires 52 are suitably secured to the ends of the windings of 45 the rotatable coils and are of sufficient length to extend to the binding posts 29, 53 and 54, which may be secured to the internal spacing member 14.

The rotatable windings are rotatably supported in the legs 31 and 33 of the U shaped members, the bearings 48 extending through apertures 55. Washers 56 are provided and positioned over the bearings and disposed between the legs of the U shaped brackets of 55 the rotatable winding to reduce friction imposed by the legs 31 and 33, which are preferably formed to flex slightly toward each other.

The internal spacing member 14 may be 60 apertured as at 57 to facilitate attaching the coil to a suitable support.

In operation, in a coil such as described, which is a radio frequency transformer having a fixed secondary 11, rotatable primary 65 13 and also a rotatable tickler coil 12, current

passing through the winding of the rotatable primary sets up a pair of parallel fields acting in opposite directions. In one position, these are in alignment with like parallel fields of the secondary winding and in full 70 accordance or coupling. 90 degrees rotation of the rotatable winding will bring the fields of the rotatable winding out of alignment or coupling with the fields of the fixed winding, any intermediate position giving a degree of 75 coupling in accordance with the degree of rotation of the rotatable windings, and thus the degree of inductance may be varied at will by rotating the rotatable winding. The tickler coil or second rotatable winding functions in a like manner and it is believed the function thereof in radio apparatus is fully understood and need not further be described. 80

While I have shown and described a radio frequency transformer having a tickler or feed-back coil, it will be understood that this type of coil may be used without the feed-back, it may be used with a fixed primary, a secondary and rotatable feed-back; and may be used as either an oscillator for modulating 85 or amplifying in any of the above combinations or the like.

It is thought that the invention and many of its attendant advantages will be understood from the foregoing description, and it 90 will be apparent that various changes may be made in the form, construction and arrangement of the parts without departing from the spirit and scope of the invention or sacrificing all of its material advantages, the 95 form hereinbefore described being merely a preferred embodiment thereof.

I claim:

1. A toroidal induction coil, comprising, a 100 fixed winding including a major portion of the toroidal form, a rotatable winding disposed within the toroidal form and between the ends of said fixed winding, internal spacing means, means for confining said fixed winding against said internal spacing means, and means for securing the parts in fixed 105 relation and providing a bearing for said rotatable winding.

2. A toroidal induction coil, comprising, a 110 fixed winding including a major portion of the toroidal form, a plurality of rotatable windings disposed within the toroidal form and between the ends of said fixed winding, internal spacing means, means for confining said fixed winding against said internal spacing means, and means for securing the parts in fixed 115 relation and providing bearings for said plurality of rotatable windings.

3. A toroidal induction coil, comprising a 120 fixed winding having adjacent and parallel toroidal fields, a rotatable winding having adjacent and parallel fields disposed within the toroidal form, and means for supporting 125 said fixed and said movable winding in operative relation, said movable winding being 130

movable between positions wherein the fields thereof will be in accordance with the fields of said fixed winding and positions wherein said fields will not be in accordance therewith.

4. A toroidal induction coil comprising a fixed winding suitably mounted and arranged

to generate adjacent and parallel toroidal fields, and a plurality of rotatable coils disposed within the toroidal form and in substantial prolongation thereof, said rotatable coils being adjustable relative to themselves and to the fixed winding.

PAUL H. DAVIS.
